M. GREENWAY

ATTACHMENT FOR SWIFTS

Filed Dec. 22, 1924

UNITED STATES PATENT OFFICE.

MARRIETT GREENWAY, OF PATERSON, NEW JERSEY, ASSIGNOR OF ONE-THIRD TO CHARLES EHRENTRAUT AND ONE-THIRD TO GEORGE HINDLE, BOTH OF PATERSON, NEW JERSEY.

ATTACHMENT FOR SWIFTS.

Application filed December 22, 1924. Serial No. 757,385.

To all whom it may concern:

Be it known that I, MARRIETT GREENWAY, a citizen of the United States, residing at Paterson, in the county of Passaic and State 5 of New Jersey, have invented certain new and useful Improvements in Attachments for Swifts, of which the following is a specification.

The operations preliminary to forming a 10 cop, quill or other wound package usually include winding the yarn or thread on a reel, with crosses in the skein formed on the reel, and then collapsing the reel and removing the skein and fitting it to a rotary structure termed a swift, which is both portable and of such light weight that in winding the package it offers no resistance sufficient to rupture the yarn. The crosses are necessary to keep the skein in such order that the windings may be delivered without snarling and breaking in the forming of the wound package, especially as in many instances the skein 20 in the meanwhile undergoes dyeing, and also to facilitate locating a break in the yarn 25 during the winding of the package. They are maintained by lease cords passed between the crossed groups of windings after the skein is formed on the reel and before it is removed therefrom, being necessarily removed after the skein has been placed on the 30 swift so that the unwinding from the swift can proceed. In the case of many yarns these crosses will remain in fairly well defined arrangement without special means to hold them while the unwinding is going on; but in the case of the more intractable yarns (i. e., yarns which are stiff and have superior "life") the slightest disturbance such as that incident merely to withdrawing the 35 yarn in unwinding, especially if the yarn has undergone dyeing, will obliterate them and the skein will assume such disorder that it is practically impossible to proceed. In consequence it is very difficult to unwind 40 from swifts in the forming of packages of material of this nature, such as artificial silk.

My principal object is to provide a swift 45 with means which will keep the crosses of the yarn well defined and intact, and to this end I provide yarn-supporting cross-pieces having radial separators for the crossed groups of windings, these having precipitate sides and also projecting to an extent suffi-

cient to protrude through the skein so that 55 the threads of the several groups cannot shift laterally over and past the separator. It is a further object of this invention to provide a yarn-supporting cross-piece which may be readily assembled with a swift and 60 particularly the type of swift having pairs of spokes and connectors joining the spokes in each pair.

In the drawing, Fig. 1 is a front elevation of a swift embodying the invention; Fig. 2 is a fragmentary side elevation; Fig. 3 is a front elevation of the cross-piece, removed;

Fig. 4 is a side elevation thereof; and 70 Fig. 5 a plan view of said cross-piece, showing the spokes of the swift in section.

The swift shown is of the type having the mentioned pairs of arms or spokes, *a* being its hub and *b* its pairs of spokes. 75

The spokes of each pair are bridged by cord connectors, forming supports substantially parallel with the swift axis, which may be either cords *c* with loops at their ends fitted over the respective spokes, as 80 shown in Figs. 1 and 2, or endless cords *d* fitted over the spokes, as in Fig. 5. These cords may as usual be slipped radially inward or outward on the spokes either in effect to collapse the swift or increase its 85 effective diameter.

Describing the cross-piece shown in the accompanying drawing and adapted for application in particular to the swift there illustrated, the same consists of a strip or 90 plate *e* preferably composed of some light and durable material like fibre, which is recessed in some way (as forked) at its ends so as to receive and be slidable and guided radially with respect to a pair of the spokes 95 of the swift. Upstanding from it are the pegs *e'*, these forming the separators and having their sides precipitate as shown in Fig. 1 and being of such length as to protrude through the skein whose thickness in 100 Fig. 1 is indicated by the dotted lines *B B*. There may be any suitable number (usually three) of these separators and they are spaced apart a distance equal to the width of each of the crossed groups of yarn windings, the margins of which are indicated by the dot-and-dash lines *A* in Fig. 1. On the under side of the plate *e* are lugs *e*², prefer-

ably two in number, and these are perforated in a line parallel with the plane of and extending longitudinally of the plate. The apertures of these lugs have threaded 5 through them the connector *c* or *d* when the cross-piece is assembled with the swift as shown in the drawing, where the cross-piece appears radially outward of and resting on the connector, its end recesses receiving the 10 spokes and its separators projecting radially outwardly. In collapsing or increasing the effective diameter of the swift each connector and cross-piece will be movable as one when thus coupled together.

15 When a swift has been equipped with the devices of this invention the attendant in fitting the skein to the swift arranges its crossed groups of windings so that they will alternate with the several separators where 20 they cross any particular cross-piece, not removing the lease cords until this arrangement has been established. Thereupon, however intractable the yarn may be, the unwinding to form the package may proceed 25 without any entangling or troublesome disturbance of the windings whatever, and if a break occurs in the windings it is readily discernible.

I am aware that swifts have been provided with cross-pieces which are serrated or roughened on their radially outer surfaces. These serrations or roughenings, however, are merely intended to keep the skein more or less in its initially spread 30 condition, and they have no influence nor are they intended to keep groups of windings or even individual windings permanently separated from start to finish of the unwinding operation, principally because they are 35 not only not high enough to be effective for this purpose but have inclined sides which allow intractable yarn to creep sidewise over them. Only the innermost layers of windings are influenced by these serrations, in any 40 event, the bulk of the skein being left entirely uncontrolled except by the mere massing of the windings which is entirely insufficient in the case of artificial silk and other 45 intractable yarns to prevent "losing the

cross," as it is called, and the snarling of the 50 windings.

Aside from the particular form of the spreader which the member *e* with its separators *e'* constitutes it is new, so far as I am aware, to provide one which has means 55 to couple it with a supporting member (as *c* or *d*, in the present example) extending substantially parallel with the swift axis so that when coupled therewith it will be shiftable with such member radially of the 60 swift; and specifically it is new to construct the coupling portion with an aperture through which said member is made to extend.

Having thus fully described my invention, 65 what I claim is:

1. A swift including a skein-supporting cross-piece having projecting therefrom substantially radially outwardly spaced separators having precipitate sides and projecting to an extent sufficient to protrude through the skein placed on the swift and adapted to receive between them and positively maintain separated the crossed groups 70 of skein windings.

2. In combination, with a swift having pairs of spokes and connectors each joining and slideable radially of the swift on the members of each pair of spokes, a spreader consisting of a strip engaged with and 80 guided by a pair of the spokes and having a lug projecting radially inward and penetrated by the corresponding connector.

3. In combination, with a swift having pairs of spokes and connectors each joining 85 and slideable radially of the swift on the members of each pair of spokes, a spreader consisting of a strip engaged with and guided by a pair of the spokes and having portions projecting radially with respect to the 90 swift, some of said portions projecting outward and being spaced and adapted to receive between them the skein windings and another projecting inward and engaged with the corresponding connector.

In testimony whereof I affix my signature.

MARRIETT GREENWAY.
